UNITED STATES PATENT OFFICE.

CHARLES W. GRAY, OF CHATTANOOGA, TENNESSEE.

MOISTENING DEVICE.

No. 870,234.

Specification of Letters Patent.

Patented Nov. 5, 1907.

Application filed August 31, 1906. Serial No. 332,748.

To all whom it may concern:

Be it known that I, CHARLES W. GRAY, a citizen of the United States, residing at Chattanooga, in the county of Hamilton and State of Tennessee, have invented a certain new and useful Improvement in Moistening Devices, of which the following is a full, clear, concise, and exact description, reference being had to the accompanying drawings, forming a part of this specification.

10 My invention relates to devices for moistening envelopes, and has several objects in view, as will appear from a description of the accompanying drawing, showing the preferred embodiment of the invention.

In the drawing—Figure 1 is a plan view of the preferred embodiment of the invention. Fig. 2 is a view in end elevation, partially in section, on line 2 2 of Fig. 1. Fig. 3 is a sectional elevation taken through a plane containing the axes of the two cylinders preferably entering into the construction of the machine.

20 Like parts are indicated by similar characters of reference throughout the different figures.

I have indicated a standard *a* that carries bearings *b*, *b*, *c*, *c* for hollow cylinder rollers *d* and *e*, these rollers being provided with stub shafts at their ends for en-

25 gagement with said bearings. The said cylinders are provided with stoppers as indicated at *f* and *g*, upon the removal whereof water may be passed into the cylinders. The cylinders are provided with perforations *h* and *i*, preferably at their forward ends, each perfora-

30 tion desirably being confined to the upper segment of each cylinder. The cylinders, by being counter-weighted at points *k* and *l* opposite the said perforations, are normally placed in position with said perforations uppermost. The portions of the cylinders where the

35 perforations are disposed, are surrounded by rings of absorbent material *m* and *n* that are charged with the water permitted to flow through the perforations.

The cylinders are provided with vent openings *o* and *p* disposed opposite to the perforations, through which

40 openings, when the cylinders have been given a half turn, air may pass to promote the passage of water through the perforations, said openings at the time being unsealed, of course. Normally, the vent openings *o* and *p* should be sealed, to which end some such

45 device as rubber bands *q*, *r* may be employed.

The upper moistening cylinder *m* is designed to moisten the gummed edges of the envelop flaps, while the lower moistening cylinder *n* is provided to moisten the portions of the envelope where the stamps are usually located, to which end the operator in passing the envelopes between the rollers, applies thumb pressure to the envelopes as they are about to issue from between the rollers, to bring the envelopes into contact with the moistening cylinder *n*. The cylinders *m*, *n*

50 are desirably off-set, as indicated most clearly in Fig. 3, so that the cylinder *m* may be in position to moisten

the flaps while the cylinder *n* is in position to moisten the stamp receiving surfaces. In order that the envelops may not be kinked in their passage between the cylinders or rollers, the rings or cylinders of felt 30 *m*, *n* do not overlap vertically where they meet, but their peripheries at the meeting point are substantially in line. In view of this last feature of construction, I employ a filling device, preferably in the form of a plurality of rings *s*, that serve to hold the flaps of 65 the envelops in engagement with the cylinder *n*.

The envelops upon issuing from the moistening device, are passed between the converging members *t*, *u* of a folding device, which partially closes the flaps and gives them a set, so that they may thereafter be 70 quickly pressed into place by hand or suitable machine. The diverging ends of the folding plates *t* and *u* face the rollers, while the converging ends are furthest away from the rollers. The upper margin of the folding plate *t* is desirably obliquely disposed with respect to the axes of rotation of the cylinders, the portion of the margin next to the rollers being further to the rear than the portion of the margin furthest removed from the rollers.

75 While I have herein shown and particularly described the preferred embodiment of my invention, I do not wish to be limited to the precise construction shown, as changes may readily be made without departing from the spirit of the invention, but,

Having thus described my invention, I claim as new 85 and desire to secure by Letters-Patent the following:

1. A device of the class described including two moistening rollers having displaced axes, one roller projecting beyond the other, whereby one roller is particularly adapted for moistening envelop flaps and the other roller 90 is particularly adapted for moistening portions of the envelops that are to receive the stamps.

2. A device of the class described including two moistening rollers having displaced axes, one roller projecting beyond the other, whereby one roller is particularly 95 adapted for moistening envelop flaps and the other roller is particularly adapted for moistening portions of the envelops that are to receive the stamps, the moistening peripheries of said rollers being substantially in line where the rollers meet to prevent the envelops from being 100 kinked.

3. A device of the class described including two moistening rollers having displaced axes, one roller projecting beyond the other, whereby one roller is particularly adapted for moistening envelop flaps and the other roller 105 is particularly adapted for moistening portions of the envelops that are to receive the stamps, the moistening peripheries of said rollers being substantially in line where the rollers meet to prevent the envelops from being kinked, the filler ring or rings surrounding the roller companion 110 to the flap moistening roller for holding the flaps against the flap moistening roller as the envelops pass between the rollers.

4. A device of the class described including two moistening rollers having displaced axes, one roller projecting 115 beyond the other, whereby one roller is particularly adapted for moistening envelop flaps and the other roller

is particularly adapted for moistening portions of the envelopes that are to receive the stamps, said moistening rollers including perforated water-containing cylinders and rings of absorbent material surrounding the cylinders where the perforations are located, which rings of absorbent material convey the moisture to the envelopes.

5. A device of the class described including two moistening rollers having displaced axes, one roller projecting beyond the other, whereby one roller is particularly 10 adapted for moistening envelop flaps and the other roller is particularly adapted for moistening portions of the envelopes that are to receive the stamps, the moistening peripheries of said rollers being substantially in line where the rollers meet to prevent the envelopes from being kinked, said moistening rollers including perforated water-containing cylinders and rings of absorbent material surrounding the cylinders where the perforations are located, which rings of absorbent material convey the moisture to the envelopes.

15. 6. A device of the class described including two moistening rollers having displaced axes, one roller projecting beyond the other, whereby one roller is particularly adapted for moistening envelop flaps and the other roller is particularly adapted for moistening portions of the envelopes that are to receive the stamps, the moistening peripheries of said rollers being substantially in line where the rollers meet to prevent the envelopes from being kinked, the filler ring or rings surrounding the roller companion to the flap moistening roller for holding the flaps against 20 the flap moistening roller as the envelopes pass between the rollers, said moistening rollers including perforated water-containing cylinders and rings of absorbent material surrounding the cylinders where the perforations are located, which rings of absorbent material convey the moisture to the envelopes.

30. 7. A device of the class described including two moistening rollers having displaced axes, one roller projecting beyond the other, whereby one roller is particularly adapted for moistening envelop flaps and the other roller is particularly adapted for moistening portions of the envelopes that are to receive the stamps, said moistening rollers including perforated water-containing cylinders and rings of absorbent material surrounding the cylinders where the perforations are located, which rings of absorbent material convey the moisture to the envelopes.

35. ent material convey the moisture to the envelopes, said perforations extending throughout segments of the cylinders.

8. A device of the class described including two moistening rollers having displaced axes, one roller projecting beyond the other, whereby one roller is particularly adapted for moistening envelop flaps and the other roller is particularly adapted for moistening portions of the envelopes that are to receive the stamps, the moistening peripheries of said rollers being substantially in line where the rollers meet to prevent the envelopes from being kinked, said moistening rollers including perforated water-containing cylinders where the perforations are located, which rings of absorbent material convey the moisture to the envelopes, said perforations extending throughout segments of the cylinders.

5. 9. A device of the class described including two moistening rollers having displaced axes, one roller projecting beyond the other, whereby one roller is particularly adapted for moistening envelop flaps and the other roller is particularly adapted for moistening portions of the envelopes that are to receive the stamps, the moistening peripheries of said rollers being substantially in line where the rollers meet to prevent the envelopes from being kinked, the filler ring or rings surrounding the roller companion to the flap moistening roller for holding the flaps against the flap moistening roller as the envelopes pass between the rollers, said moistening rollers including perforated water-containing cylinders and rings of absorbent material surrounding the cylinders where the perforations are located, which rings of absorbent material convey the moisture to the envelopes, said perforations extending throughout 70 segments of the cylinders.

10. A device of the class described including a moistening roller comprising a water-containing cylinder perforated throughout a segmental portion thereof, and a ring of absorbent material surrounding the material where the cylinder perforations are located, said cylinder being counter-weighted to maintain said perforations normally uppermost.

In witness whereof, I hereunto subscribe my name this twenty ninth day of August A. D., 1906.

CHARLES W. GRAY.
